UNITED STATES PATENT OFFICE.

EDWIN W. GORSUCH, OF BALTIMORE, MARYLAND.

SHOE STRUCTURE FOR TRAIN-CONTROL SYSTEMS.

1,221,310.

Specification of Letters Patent.

Patented Apr. 3, 1917.

Original application filed December 11, 1915, Serial No. 66,284. Divided and this application filed August 16, 1916. Serial No. 115,213.

To all whom it may concern:

Be it known that I, EDWIN W. GORSUCH, a citizen of the United States, residing at Baltimore, in the State of Maryland, have 5 invented certain new and useful Improvements in Shoe Structures for Train-Control Systems, of which the following is a specification, reference being had therein to the accompanying drawing.

10 This invention relates to improvements in shoe structures for train control systems, one object of the invention being the provision of a shoe adapted to engage a ramp rail and which is simple, durable, and inexpensive in 15 construction, and thoroughly efficient and practical in use.

15 A further object of this invention is the provision of a shoe for coöperation with a ramp rail to actuate a venting valve for an 20 air brake system, the main structure of which is made from an integral piece of metal and comprises substantially two curved arms having a supporting terminal by means of which the shoe is mounted for 25 swinging movement and a U-shaped valve engaging member bridging the opposite terminal, there being provided a removable wear resisting member adjacent the U-shaped member for engaging the ramp rail.

30 This application in part is a division of my application for improvements in automatic train control systems, filed December 11, 1915, Serial Number, 66,284.

In the accompanying drawings:

35 Figure 1 is a longitudinal sectional view through the support for the present shoe and the valve controlled thereby, the valve and other mechanism being shown merely to indicate the relative position of the shoe.

40 Fig. 2 is a perspective view of the shoe *per se*.

Fig. 3 is a perspective view of the supporting end of a modified form of shoe.

45 Fig. 4 is a longitudinal sectional view through the supporting platform and the forward end of the shoe, as shown in Fig. 3.

Fig. 5 is a bottom plan view of that portion of the mechanism shown in Fig. 4.

Referring to the drawings, the numeral 10 50 designates the platform or supporting base which is hung in any desired manner from the vehicle carrying the same, and has mounted thereupon the air brake controlling mechanism 11, the detail construction of

which is particularly set forth in my before- 55 mentioned application, while attached to the under side of the platform 10 by means of the bolts 12 is a sheet 13 of insulation which receives the metal plate 14 carrying the downwardly projecting obstruction removing 60 arms 15. The bolts 12 are mounted in bushings 16 of insulation.

Also supported by the bolts 12 are the two clamping plates 17 and 18, each supporting therebetween a series of plates 19, which 65 with the clamping plates 17 and 18, provide an adjustable support for the bushings 20 which are carried upon the reduced portions 21 of the bridging and connecting plate 22 of the shoe 23.

70 This shoe, as clearly illustrated in Figs. 1 and 2, consists of the two curved arms 24 connected at their opposite terminals by the bridging strip 25 which has riveted or otherwise secured thereto as at 26 the ramp rail 75 engaging and wear resisting plate 27 which is of a harder material than the shoe, so that when the same is worn, a new one may be substituted without changing the shoe.

A U-shaped member 28 which is also carried by the free terminals of the arm 24 is adapted to fit astride of the platform 10 and be disposed in coöperative relation with the valve mechanism 11.

80 In the construction shown in Figs. 3, 4, 85 and 5, the obstruction engaging arms 15' are secured to the platform 10' by means of bolts 29, so that the rearwardly extending arm 30 having the hook 31 will engage intermediate of the ends thereof the sectional 90 bushing 32 which extends the full width of the supporting bar 22' of the shoe 23', while the two strap supports 33 are secured by bolts 34 to the platform 10' and receive the portions of the bushing 32 at the opposite 95 sides of the hook 31. As the shoe 23' has a limited swinging movement, it has been found in practice that a sectional bushing such as here set forth and shown will operate properly and will reduce the cost of installation and maintenance.

100 As shown in Figs. 1 and 2, each arm 24 is provided with an opening 35 for the reception of the lower end of the respective rods 36 which extend upwardly for sliding movement through openings in the platform 10, and are guided in the inverted cylindrical casings 37 so that the spring 38 mounted

upon each rod 36 will bear against the casing 37 and the shoe to resiliently hold the shoe with its free end downwardly.

This construction is adapted to be applied 5 to both forms of shoe here illustrated.

What I claim as new is:—

1. In a train control apparatus, a support, two spaced curved arms connected by 10 a journaling connection, a ramp abutting member bridging the opposite ends of said arms, and a U-shaped bridging member having its terminals connected to said curved arms.

2. In a train control apparatus, a suitable 15 support, two spaced curved arms, a flat connection between the two arms at one end thereof, a bushing surrounding the connection and journaled to the support, a ramp abutting member bridging the opposite ends 20 of the arms, and a U-shaped bridging member having its terminals connected to the arms.

3. A ramp actuated shoe for train control 25 systems, including two curved arms, a flat strip connecting the supporting ends of said arms, and a removable ramp engaging member of greater wear resisting material than the arms connected to the other ends of the arms.

30 4. A ramp actuated shoe for train control systems, including two curved arms, a flat strip connecting the supporting ends of said arms, a removable ramp engaging member of greater wear resisting material than the arms connected to the other ends of the arms, and a U-shaped member attached to both arms.

40 5. A ramp actuated shoe for train control systems, including two curved arms, a flat strip connecting the supporting ends of said arms, a removable ramp engaging member of greater wear resisting material than the arms connected to the other ends of the

arms, and a U-shaped member having the terminals thereof connected to the curved 45 arms adjacent the ramp engaging member.

6. A ramp actuated shoe for train control systems, including two curved arms, a flat strip connecting the supporting ends of said arms, a removable ramp engaging member 50 of greater wear resisting material than the arms connected to the other ends of the arms, two rods pivotally connected to the curved arms intermediate of their ends, and a spring mounted upon each rod for resiliently holding the arms downwardly. 55

7. A ramp actuated shoe for train control systems, including two curved arms, a flat strip connecting the supporting ends of said arms, a removable ramp engaging member 60 of greater wear resisting material than the arms connected to the other ends of the arms, two rods pivotally connected to the curved arms intermediate of their ends, a spring mounted upon each rod for resiliently holding the arms downwardly, and a U-shaped member having the terminals thereof connected to the curved arms adjacent the ramp engaging member. 65

8. The combination with a platform, of 70 a ramp engaging shoe structure including two curved arms, a bridging member connected to two ends thereof and forming a pivotal support for said arms, a strip bridging the free ends of said arms and forming 75 a ramp engaging portion, a valve engaging member carried by the free ends of said arms and disposed to fit astride the support, two rods connected pivotally intermediate of the ends of the curved arms, two casings mounted upon the support, and forming guides for 80 said rods, and a spring mounted upon each rod and exerting pressure upon its casing and its arm to resiliently depress the shoe. 85

In testimony whereof I affix my signature. EDWIN W. GORSUCH.
